ATTORNEYS

UNITED STATES PATENT OFFICE.

PHILIP C. ANDERSON, OF RAPID CITY, SOUTH DAKOTA.

SCRAPER.

Application filed February 15, 1923. Serial No. 619,228.

To all whom it may concern:

Be it known that I, PHILIP C. ANDERSON, a citizen of the United States, and a resident of Rapid City, in the county of Pennington and State of South Dakota, have invented a new and useful Improvement in Scrapers, of which the following is a full, clear, and exact description.

My invention relates to improvements in scrapers, more particularly to scrapers for use on road construction or the like, and it consists in the combinations, constructions, and arrangements herein described and claimed.

15 An object of my invention is to provide a scraper in which use is made of a scraper bucket which is mounted on wheels, the wheels being, however, in the rear of the bucket, thereby enabling the latter to get into places where the ordinary center-wheeled bucket could not enter.

A further object of my invention is to provide a scraper of a wheeled-bucket type, which is provided with a power dump, thus 25 obviating the labor necessary to dump the load.

A further object of my invention is to provide a bucket which is pivoted at its front end, thus enabling the rear end to be raised 30 for dumping, and permitting the front end of the bucket to act as a leveler to float or spread out the material being dumped.

A further object of my invention is to provide novel means for raising the bucket from the ground after it is loaded and for subsequently tilting it to discharge the load.

40 A further object of my invention is to provide a device in which the wheels of the bucket, which, as stated, are disposed in the rear of the latter, are also within the side edges of the bucket, thereby preventing the raising of the bucket, as would be the case were the wheels farther apart than the width of the bucket, when they encounter a rock 45 or other obstacle outside of the path of the bucket.

A further object of my invention is to provide a wheeled scraper of such a form that it can be made up into a train of 50 trailers, which may be drawn by a tractor, and with which sharp turns can be made.

Other objects and advantages will appear in the following specification, and the novel features of the invention will be particularly pointed out in the appended claims.

My invention is illustrated in the accompanying drawings, forming part of this application, in which—

Figure 1 is a perspective view of the scraper, 60

Figure 2 is a plan view,

Figure 3 is an enlarged sectional view substantially on the line 3—3 of Figure 2,

Figure 4 is a diagrammatic view showing a series of trailer units, 65

Figure 5 is a detail view showing a portion of the dumping mechanism,

Figure 6 is a sectional detail view of a portion of the clutch mechanism,

Figure 7 is a sectional view along the line 70 7—7 of Figure 6, and

Figure 8 is a diagrammatic view showing the manner of supporting adjacent trailers.

In carrying out my invention, I provide an oblong frame 1, preferably of channel 75

iron, the ends tapering toward the center as shown at 2. Secured to the under portion of the frame near one end thereof are brackets, such as that shown at 3, in which are journaled the ends of an axle 4. Carried 80

by the axle 4 are wheels 5, which, as will be observed from Figure 2, are within the sides of the frame 1. One end of the axle 4 bears a sprocket wheel 6 (see Figures 1 and 6),

which is loosely mounted for rotation on the 85 axle, being next to a collar 7 which prevents the movement toward the body portion of the vehicle.

The hub 8 of the sprocket wheel 6 is provided with teeth 9 arranged to engage similar teeth on a slideable clutch member 10, which is feathered to the shaft 4, but

which may be shifted to cause the rotation 90 of the sprocket wheel 6 by means of a yoke 11, which is mounted on a vertically extending

rock shaft 12 (see Figures 1 and 5) carried by a bracket 13, mounted on the frame 1.

The rock shaft 12 is connected with an arm 14 (see Figure 1) operated by a link 15 (see Figure 5), which is connected at the

bottom of a lever 16, which is pivotally mounted at 17, and whose movement is

adapted to throw the clutch member 10 into or out of engagement with the sprocket 6

in the manner hereinafter described.

Toward the opposite end of the frame 1 from that at which the wheels are mounted,

is a U-shaped frame portion, consisting of uprights 18 and 19 connected together at

their tops by a horizontally disposed member 20 (see Figures 1, 2 and 3). The up-

rights 18 and 19 are secured to the frame 1 by bolts 21 (see Figure 1), and are further braced by diagonal brace members 22 and 23.

Carried by the brace members 22 and 23 are bearings 24 and 25 respectively for a crank shaft 26. On one end of the crank shaft 26 is a large sprocket wheel 27 which is connected by a sprocket chain 28 with the sprocket wheel 6 on the axle 4.

10 The scraper bucket is shown in general at 29. It is provided at the forward upper corners with reenforcing plates 30 which are riveted or otherwise secured to the bucket, and which, in turn, are pivotally secured at 31 to the lower ends of the uprights 18 and 19 respectively. The rear end of the bucket is connected by means of links 32 (see Figures 2 and 3) with the central portion of the crank shaft 26, so that as the 15 crank shaft is rotated, the bucket is oscillated from its normal carrying position to the dumping position, and back to its normal position, by the mechanism hereinafter described.

25 Referring again to Figures 1, 3 and 5, it will be noted that the lever 16 which, as stated, is pivotally mounted at 17, is, in fact, a U-shaped lever, consisting of the arms 16 connected by a cross member 16^b (see Figure 30 3). The pivotal connections 17 of the U-shaped lever 16 are on the inclined frame members 22 and 23 respectively, and the manipulation of either of the levers 16 from either side of the machine will operate the 35 clutch member 10 in the manner described.

Referring now particularly to Figures 1 and 5, it will be seen that there is a bracket 33 which is secured to one of the arms of the lever 16, and which serves as a support 40 for a pivotally mounted impact member 34. The latter is normally held by springs 35 and 36 in the position shown in Figure 5. The lever has an oppositely extending crescent-shaped bar 37, to which is pivotally secured a rod 38. The latter passes into the housing 39 pivotally mounted at 40 on a bracket 41. A spring 42 presses on the collar 43^b within the housing, which collar is secured to the rod 38. The construction 45 is such that when the lever 16 is in the position shown in Figure 5, the spring 42 is exerting tension through the rod 38 on the bar 37. When the upper end of the lever is moved to the left in Figure 5, the spring 42 is compressed, and when the lever has moved far enough to bring the pivotal connection of the rod 38 with the bar 37 downwardly past the pivotal point 40, the bar and the lever are given a quick throw in the direction of their movement. The same thing 50 occurs when the lever is moved in the opposite direction.

It will be noted that the sprocket wheel 27 is provided with an arm or leg 44, which,

during the revolution of the sprocket wheel, 65 is arranged to engage the impact member 34.

Toward the rear end of the frame are inclined frame members 45 and 46, at the top of which is a bearing 47 (see Figure 1).

A bearing block 48 is secured at the front 70 end of the device. The shaft 49 is carried by the bearings 47 and 48, the rear end of the shaft being provided with a crank handle 50. A worm 51 is provided on the shaft 49, and engages a worm wheel 52 which is 75 mounted on a shaft 53 (see Figure 2), having rigidly attached thereto an upstanding arm 54. This arm is connected by means of a link 55 with a pair of bars 56 and 57 which are braced by a cross member 58. The bars 56 and 57 lie above and have substantially the same contour as the front end of the frame 2. They are pivoted to the frame 1 at the point 59 substantially underneath the axial line of the crank shaft 26. At the 80 outer ends of the converging bars 56 and 57 is a forwardly and downwardly extending brace member 60, which is rigidly secured to inclined brace members 61, the latter being extended to form a clevis 62, by means of 85 which a draw-bar 63 is attached. The shaft 53, bearing the gear 52, is mounted at one end in a bracket 64, which is braced by an inclined strut 65 secured to the forward part of the frame 2, the opposite end of the shaft 90 being journalled in the bearing 66, as shown in Figure 2.

From the foregoing description of the various parts of the device, the operation thereof may be readily understood. The device is primarily designed to be used in trains, such as that shown in Figure 4. In this figure the tractor is shown diagrammatically at A, and the scraper trailers at B, C, D, and E respectively. In manipulating 100 these trailers, the operator stands at the rear on the foot boards 67. As the train is drawn along by the tractor, the bucket of one scraper may be lowered into its operative position, i. e., the position in which it is 105 filled, by turning the handle 50. This, through the medium of the shaft 49 and the gears 51 and 52, will turn the shaft 53 and with it the arm 54. In Figure 3 the bucket 29 is shown as being drawn along the ground to be filled. When the bucket is filled, it is 110 raised in the following manner: Assuming that the arm 54 in Figure 1 is being rotated clockwise in the figure, it will cause a thrust downwardly on the member 55, but since the forward end is secured to the draw-bar of the tractor, and hence cannot move downwardly, the result will be that the frame 2 will be swung upwardly about the axle 4 as an axis, into the dotted line position shown in Figure 3, in which the bucket will be carried along clear of the ground. The operator 115 of the next trailer may lower, fill, and raise 120

his bucket by manipulating his handle 50 in the same manner. In this way the buckets are filled one at a time, and consequently require less power for their filling, than if 5 one bucket of a large capacity, say four times as large, were filled at one operation.

When the train arrives at the dumping place, either of the levers which is normally in the dotted line position shown in Figure 10 5, is pushed into the full line position. This, as has been explained before, through the medium of the rod 15, the arm 14, the rock shaft 12, and the yoke 11, will cause a quick engagement of the clutch members so as to 15 drive the sprocket wheel 27 from the shaft 4. The rotation of the crank shaft 26 will cause the bucket to take the position shown in Figure 1, thereby dumping the load. Further rotation of the sprocket will cause the 20 engagement of the lug 44 with the impact member 34, thus swinging the levers 16 into their normal dotted line position shown in Figure 5, and causing a sudden disengagement of the clutch when the bucket is in its 25 normally lowered position.

Each of the scraper buckets of the train is dumped at the proper place, and the train may be brought back to the place where the dirt is being excavated.

30 I desire to call particular attention to the fact that the tapered construction of the trailer units will permit turning in a comparatively short space, as illustrated in Figure 4. Furthermore, when the units are connected in trains, as shown in Figure 8, the wheels 5 on the rear of one unit, as for instance, the unit B, form a support for the front end of the unit C in the rear, thus enabling each unit to be provided with two 35 wheels only, and permitting the raising or 40 lowering of the bucket as described.

The position of the bucket after dumping is such that the front end of the bucket acts 45 as a scraper or leveler to float the material dumped, thus obviating the necessity of distributing the dumped material manually.

I claim:

1. A scraper comprising a frame, wheels 50 for supporting said frame, a second frame pivotally secured to said first named frame, said second named frame adapted to be attached to a tractor or the like, and to be supported thereby, a worm carried by said first

named frame, a worm gear carried by said first named frame and in mesh with said 55 worm, manually controlled means for rotating said worm, an arm carried by said worm gear, a link connecting said arm with said second named frame whereby a rotation of said worm will raise or lower said first 60 named frame with respect to said second named frame, and a bucket carried by said first named frame and adapted to be moved vertically with respect to the ground when said first named frame is moved with respect 65 to said second named frame.

2. A scraper comprising a frame, wheels for supporting said frame, a bucket pivotally carried by said frame, a crank carried by said frame and being operatively connected 70 to said bucket so as to swing the latter when said crank is actuated, means connecting said crank to said wheels, said means including a clutch and means for automatically disconnecting said clutch after said crank has made 75 one complete revolution, whereby said crank is disconnected from said wheels.

3. A scraper comprising a frame, a shaft carried by said frame, wheels mounted on said shaft, a bucket pivotally carried by said frame, a crank carried by said frame, a sprocket mounted on said crank, a second sprocket mounted on said shaft, connections between said sprockets, a clutch connecting said second named sprocket to said shaft, 80 means for throwing said clutch out of engagement with said sprocket, and means carried by said first named sprocket for actuating said clutch throwing means.

4. A scraper comprising a frame, a shaft 90 carried by said frame, wheels mounted on said shaft, a bucket pivotally carried by said frame, a crank carried by said frame, a sprocket mounted on said crank, a second sprocket mounted on said shaft, connections 95 between said sprockets, a clutch connecting said second named sprocket to said shaft, means for throwing said clutch out of engagement with said sprocket, and means carried by said first named sprocket for actuating said clutch throwing means, said clutch throwing means comprising a spring pressed lever adapted to be yieldingly held in two positions, and connections between said lever and said clutch.

PHILIP C. ANDERSON.
